LUMINOUS ELECTRICAL DISCHARGE TUBE

Filed Dec. 17, 1927

FIG. 1.

FIG. 2.

Inventor
John J. Madine

By Ernest Meloy
Attorney

UNITED STATES PATENT OFFICE

JOHN J. MADINE, OF CLEVELAND, OHIO, ASSIGNOR TO SUN' RAY GAS CORPORATION,
OF CLEVELAND, OHIO, A CORPORATION OF NEVADA

LUMINOUS ELECTRICAL DISCHARGE TUBE

Application filed December 17, 1927. Serial No. 240,903.

This invention relates to luminescent electrical discharge tubes and more particularly to tubes employing an inert gas such as neon and argon as the current conducting medium and in which a small quantity of liquid such as mercury is enclosed in the tube to supply its vapor to the gaseous medium for the purpose of imparting a desired color to the light emanating from the tube.

10 In signs made of luminescent tubes of the character above referred to in which a small quantity of mercury or other substance such as an amalgam, sodium or potassium, is employed for imparting color to the light, 15 the said substance is apt to become displaced from the end of the tube in setting up a sign, with the result that the tube when in operation has the substance so placed therein that it is subjected to very little of the 20 heat generated by the passage of electric current through the tube, and consequently at times when the atmospheric temperature is low sufficient vapor is not given off to materially affect the color of the light.

25 The present invention has for its object to provide a tube in which the liquid or substance is trapped in the end of the tube in contact with or adjacent an electrode so that it cannot flow into the body of the tube 30 when the sign is tipped in the handling thereof.

A further object is to provide a liquid trap which will permit the vapor to pass readily from the trap into the body of the 35 tube and which will permit any liquid in the body of the tube to readily flow into the trap at the end of the tube.

With the above and other objects in view, 40 the invention may be said to comprise the discharge tube as illustrated in the accompanying drawings hereinafter described and particularly set forth in the appended claims, together with such variations and 45 modifications thereof as will be apparent to one skilled in the art to which the invention appertains.

Referring to the accompanying drawings forming a part of this specification, 50 Figure 1 is a fragmentary view of the

tube, partly in longitudinal section and partly in side elevation.

Fig. 2 is a section taken on line 2—2 of Fig. 1.

Referring to the accompanying drawings, 55 the discharge tube consists of a body portion 1 formed of glass tubing which may be bent to any desired configuration to form a suitable sign or part of a sign, the ends of the glass tubing being closed by thimble shaped 60 metal electrodes 2 in the open ends of which the ends of the glass tubing are sealed. The end of the glass tubing adjacent the electrode is provided with a partition member 3 integrally united with the body of the 65 tubing and provided with a tubular central projection 4 which extends towards the bottom of the electrode and forms a central passage or opening 5 establishing communication between the interior of the electrode 70 and the body of the tube. The tubular projection 4 forms with the main tube an annular space 6 which, when the tube is tipped to an angle which would cause the liquid to 75 flow toward the body 1 of the tube, will receive the liquid such as the mercury 7 shown in Fig. 1 and prevent the liquid from escaping from the electrode. The partition member thus forms a liquid retaining chamber at 80 the end of the tube which serves as a trap preventing the escape of liquid from the electrode, the central passage 5 permitting the vapor of the mercury or other liquid to 85 pass freely into the body of the tube and to mingle with the gaseous current conducting medium which fills the tube.

In the operation of the tube, during cold weather, there may be condensation of mercury in the glass body portion 1, but any mercury accumulating in the body portion 90 of the tube may be returned to the electrode by simply tipping the tube to an angle such that the mercury will flow to the partition 3 and through the passage 5 into the mercury chamber. By maintaining the mercury 95 in contact with the electrode with a relatively large area of contact between the electrode and the body of mercury, heat generated in the electrode by the passage of the electrical current is transmitted directly to 100

the mercury, so that vaporization of the mercury sufficient to maintain the characteristic mercury vapor only throughout the tube is insured.

5 Furthermore, it is to be understood that the particular form of apparatus shown and described, and the particular procedure set forth, are presented for purposes of explanation and illustration and that various modifications of said apparatus and procedure 10 can be made without departing from my invention as defined in the appended claims.

What I claim is:

15 1. A luminescent electric discharge tube comprising a body of glass tubing having a thimble shaped electrode sealed to an end thereof, the end of said glass tubing being formed to provide a trap for retaining mercury within the electrode in contact therewith, and having an opening for the 20 passage of mercury vapor to the interior of the glass tubing.

25 2. A luminescent electric discharge tube comprising a body of glass tubing having a thimble shaped electrode sealed to an end thereof and adapted to serve as a container for mercury, the end of said glass tubing having a partition forming a chamber for retaining mercury in the electrode, said partition having a central tubular extension 30 projecting into the chamber and providing an annular mercury retaining recess and a central passage permitting flow of mercury vapor from the chamber or mercury into 35 the tube.

40 3. A luminescent electric discharge tube comprising a glass tube, an electrode closing an end of the glass tube and having mercury supported in contact with the interior surface thereof, a partition member adjacent the electrode and formed integral with the glass tube, said partition member co-operating with the electrode to form a mercury retaining chamber, said partition member 45 having a tubular portion extending into the chamber and spaced from the tubular wall thereof, said tubular portion forming an outlet passage for mercury vapor.

In testimony whereof I affix my signature.

50 JOHN J. MADINE.
